UNITED STATES PATENT OFFICE.

GEORGE F. ROSE, OF HYNDSVILLE, NEW YORK.

TYPEWRITER.

Application filed December 9, 1921. Serial No. 521,227.

To all whom it may concern:

Be it known that I, GEORGE F. ROSE, citizen of the United States, and resident of Hyndsville, in the county of Schoharie and State of New York, have invented certain new and useful Improvements in Typewriters; and I do hereby declare the following to be a full, clear, and exact description of the same, reference being had to the accompanying drawings forming a part of this specification and to the reference numerals marked thereon.

This invention relates to typewriting machines and more especially to features applicable, for example, to machines of the striking type bar variety, one object of the invention being to provide a compact and practical form of construction and arrangement of parts for producing a machine of this character of reduced size and weight particularly adapted, for instance, for use as a portable type of machine. Another object is the provision of such a machine having an advantageous supporting means or bridge for the key levers. To these and other ends the invention resides in certain improvements and combinations of parts all as will hereinafter be more fully described, the novel features being pointed out in the claims at the end of the specification.

In the drawings:

Figure 1 is a side elevation of a typewriting machine embodying the present invention;

Figure 2 is a top plan view of a portion of the forward end of the machine showing the key levers and the supporting means therefor;

Figure 3 is an enlarged top plan view of the key lever supporting means or bridge with the cover plate removed;

Figure 4 is a sectional elevation on the line 4^a—4^a of Figure 2;

Figure 5 is a sectional elevation on the line 5^a—5^a of Figure 2;

Figure 6 is a section on the line 6^a—6^a of Figure 4;

Figure 7 is a section on the line 7^a—7^a of Figure 4; and

Figure 8 is a section on the line 8^a—8^a of Figure 4.

Similar reference numerals throughout the several views indicate the same parts.

The embodiment of the invention selected for the purposes of the present disclosure to illustrate the principles involved and a pre-

ferred practical application of the same is shown in conjunction with a striking bar typewriting machine having a main frame indicated generally at 10, which may be of the usual or any suitable variety, adjacent the rear of which is supported a traveling work carriage 11 including a roller platen 12. At 13 is a suitable ribbon supporting and feeding mechanism. The carriage is moved longitudinally by a suitable motive means (not shown) and its movement controlled or spaced by mechanism including a contact bar 14 positioned for engagement by the type bars, this construction representing a type of machine well known in the art.

The present invention is applied in this instance to a machine of the type described above, comprising a construction and arrangement of type bars and key levers and their supporting means of a compact nature providing for reduction in the size and weight of the machine and including a simple form of construction for the key lever bridge affording an efficient supporting means comprising but few parts inexpensive to manufacture.

Referring more particularly to the drawings, the type bars 15 are supported, preferably, on a transverse wall or plate 16 located forwardly of the platen and inclined upwardly and rearwardly at a substantial angle with the perpendicular. Wall 16 is supported at its ends on the sides of the frame and has fixed on its forward side a sector shaped member 17 pivotally supporting the rear ends of the type bars, this sector member having any suitable form of construction such for example as that disclosed in my co-pending application Serial No. 523,317 filed December 19, 1921 for typewriter construction. The type bars are actuated by connections, such, for example, as links 18, with the rear ends of key levers 19 constructed and supported as hereafter described, and arranged in groups or banks as shown. The type bars are sustained in inactive position by an abutment or support of the usual construction (not shown) which is in the present case so positioned as to support the bars at an inclination upwardly and forwardly of the machine as shown in Figure 1. The location of the pivotal support for the bars forwardly of the platen provides for the arrangement of the bars in platen striking position at an inclination upwardly and rearwardly of the machine.

This striking position of the bars permits of the support of the platen at a lower elevation than would be possible if the bars were arranged for a vertical striking position.

5 In other words while the type bars swing through a vertical position in striking, they move from an inclined position of rest to a correspondingly inclined striking position, thereby reducing the necessary height of 10 the machine.

In addition to the reduction of the overall vertical dimensions of the machine, the above described arrangement, including the inclined inactive position of the type bars, 15 provides space beneath the forward ends of the latter when in inactive position for the reception of the rear ends of the key levers and the supporting means for the same. This advantage is enhanced by the provision 20 of improved key lever supporting means which may be located well under the inactive type-bar position, thereby reducing the front-to-rear dimensions of the machine. This supporting means at the same time is 25 so constructed as to provide a rigid fulcrum for the levers on which they are maintained in the proper alignment and accurately guided in their movements.

The key-lever support comprises, preferably, a sheet metal plate 20, of substantially channel shape, extending transversely of the frame below the inactive type-bar position. The plate has a central top portion which is stepped or generally inclined so as 30 to lie substantially parallel with the type bars, thereby facilitating the compact positioning of the bridge below the latter and in such a manner as to leave additional space below the bridge for the reception of 35 various other parts of the machine which it is unnecessary to describe herein. Forwardly and rearwardly of this top portion of the bridge, the sides or flanges of the plate are turned downwardly as at 21 and 40 22 to provide the desired rigidity. A bottom plate 23 is preferably secured to the depending flanges 21 and 22 to close the bottom of the bridge but this may be dispensed with.

45 50 In the construction of the bridge, the plate 20 from which it is formed preferably has cut therein while in flat condition a plurality of slots 24 arranged to extend from front to rear of the machine for the 55 reception of the key levers. The flanges 21 and 22 are turned downwardly and the material of the central or top portion of the plate between the slots 24 is stamped up into longitudinally extending steps to produce the general transverse inclination 60 described and shown, and the metal of each step is struck downwardly as at 25 in lines which thus extend longitudinally of the bridge or transversely of the machine and 65 are spaced from front to rear of the latter

to correspond in number with the number of groups or banks of key levers. These portions 25 provide bearing depressions in which are pivotally supported trunnion means carried by the levers. That is to say, 70 each key lever is provided with a trunnion 26 extending from opposite sides thereof and preferably formed by a cylindrical pin or spindle passed through the lever. These trunnions of each lever lie in depressions 25 formed in the plate on either side of the corresponding lever slot. Each bank of 75 keys thus has its levers pivotally supported on a common axis extending transversely of the machine, with the axes of the different banks spaced from each other in a direction inclined to correspond with the inclination of the inactive position of the type bars.

The material of the bridge lying between the bearing depressions in each axis of support is preferably struck upward on an arc as at 27, these projections thus alternating with the depression in each axial line and being staggered relatively to each other from front to rear of machine, as shown in 80 Figure 3. By reference to the drawings it will be seen that the described depressions and projections of the metal at the sides of the slot increase the effective depth of the latter, or in other words that each lever in 85 its slot lies between depressed and elevated portions of the bridge on both sides which thus provide guide surfaces for the lever of substantial transverse extent effectively maintaining the alignment of the lever in a vertical plane. Each lever of course lies in a slot 24 of considerable length which likewise effectively maintains its longitudinal alignment, the slots 24 being accurately milled or ground after the bridge is 90 stamped up, preferably, to increase the precision of the key-lever action. It is to be noted also that the trunnion of each lever abuts at its ends the sides of adjacent levers which prevents possible displacement of the trunnions relative to their respective 95 levers.

100 Means are provided for holding the lever trunnions in their bearing depressions comprising preferably a one-piece sheet metal plate 28 of the form shown in Figure 2, having at its forward and rear sides lugs 29 and 30 respectively secured as by means of screws 31 to projections 27 of the bridge. The cover plate has projecting from its forward and rear sides, also, series of fingers 32 and 33 respectively, bent downwardly from the body of the plate to rest upon the key lever trunnions of the forward and rear axes. Plate 28 has struck downwardly 105 from its central portion a series of fingers or lugs 34 which rest upon the lever trunnions of the central axis, so that this one-piece cover maintains all of the trunnions 110 in their respective bearing depressions. 115 120 125

- The means for attaching the ends of the key-lever bridge to the side walls of the main frame comprises preferably pairs of lugs 35 turned inwardly toward each other 5 from the depending flange portion 21 and 22 of the bridge and secured to the sides of the main frame as by means of screws 36. The construction of the key-lever bridge thus comprises essentially but two parts, the 10 bridge proper or plate 20, and its cover member 28, which are economically formed from sheet metal in such a manner as to afford a rigid support, with its parts so arranged as to effectively support and guide 15 the key levers for accurate pivotal movement on their trunnions. At the same time the bridge is so designed as to combine with the described advantageous arrangement of the type bars to produce an exceedingly 20 compact construction, reducing the overall dimensions and weight of the machine which is a consideration of particular importance in machines of a portable type.
- I claim as my invention:
- 25 1. In a typewriting machine, the combination of a main frame, a platen thereon, type bars having a swinging movement from inactive to striking position, key levers operatively connected with said type bars and arranged in banks, and a bridge constructed of a single piece of material extending across the main frame for supporting the spindle means of the levers with the axes of those of each bank arranged in a common 35 center and the axes of those of different banks spaced relatively to and substantially parallel with each other.
2. In a typewriting machine, the combination of a frame, a movable platen thereon, 40 type bars movable from forwardly and upwardly inclined inactive position to upwardly and rearwardly inclined striking position, key levers operatively connected with said type bars and arranged in banks, 45 and a bridge constructed of a single piece of material extending across the frame for supporting the levers with the axes of those of each bank arranged in substantial alignment, and the axes of those of different 50 banks spaced relatively to each other and arranged in a forwardly and upwardly inclined plane.
3. In a typewriting machine, the combination of a frame, a platen movable thereon, 55 type bars, a sector in which the type bars are supported for movement from an upwardly and forwardly inclined inactive position to an upwardly and rearwardly inclined striking position, key levers arranged in banks, supporting means therefor arranged beneath the inactive position of the type bars and comprising a device constructed of a single piece of material providing pivotal axes for 60 said banks of levers spaced from each other 65 and arranged in a forwardly and upwardly inclined plane, downwardly and rearwardly inclined portions on said levers, and means connecting the rear ends of said levers with the type bars. 70
4. In a typewriting machine, the combination of a frame, a platen movable thereon, type bars, a transverse member on the frame forwardly of the platen and inclined upwardly and rearwardly toward the platen, means on said member for pivotally supporting the type bars for movement from an upwardly and forwardly inclined position of rest to an upwardly and rearwardly inclined striking position, supporting means constructed of a single piece of material and arranged beneath the type bars when in their inactive position, and a plurality of key levers pivoted on said supporting means and extending downwardly and rearwardly and operatively connected with the type bars. 75
5. In a typewriting machine the combination of a main frame, a platen thereon, type bars having a swinging movement on the frame from an upwardly and forwardly inclined inactive position to an upwardly and rearwardly inclined platen striking position, key levers connected with said type bars and arranged in banks, and a sheet metal key lever bridge arranged on the frame below said inactive type bar position at an inclination corresponding substantially with the latter and formed to provide supports spaced in the direction of inclination for the different banks of levers. 80
6. In a typewriting machine, the combination of a main frame, a platen thereon, striking type bars on the frame having an inactive position inclined upwardly and forwardly of the machine, a sheet metal support arranged on the frame below said inactive type bar position at an inclination corresponding substantially with the latter and formed with slots for the reception of key levers, the strips of the support between said slots being struck upwardly and downwardly to form projections and depressions for guiding said levers, and key levers having portions extended through said slots downwardly and rearwardly of the machine 105 for connection with said type bars and provided with trunnions pivotally carried in said depressions of the support. 110
7. In a typewriting machine, the combination of a main frame, a platen thereon, striking type bars on the frame having an inactive position inclined upwardly and forwardly of the machine, key levers disposed in banks, a sheet metal support arranged on the frame below said inactive type bar position and inclined upwardly and forwardly to correspond to the position of the latter and formed with guide slots to receive the key levers, said support having bearing depressions formed therein extending trans- 120 125 130

- versely of the machine and spaced from one another from front to rear of the latter to correspond with the different banks of key levers, means carried in said depressions 5 for pivotally supporting the corresponding levers, and actuating connections between the levers and type bars.
8. In a typewriting machine, the combination of a main frame, a platen thereon, 10 striking type bars on the frame having an inactive position inclined upwardly and forwardly of the machine, key levers disposed in banks and connected with the type bars, a sheet metal support arranged on the frame 15 below said inactive type bar position and inclined upwardly and forwardly to correspond to the position of the latter and formed with guide slots to receive the key levers, said support having bearing depressions formed therein extending transversely 20 of the machine and spaced from one another from front to rear of the latter to correspond with the different banks of key levers, trunnions pivotally supporting the levers in 25 the corresponding depressions, and a plate on said support provided with means for retaining said trunnions in said depressions.
9. In a typewriting machine, the combination with a frame and key levers thereon 30 arranged in groups, of supporting means on the frame for said levers comprising a one piece sheet metal bridge having bearing portions struck therefrom extending transversely of the machine in lines spaced relatively 35 to one another from front to rear of the latter, one for each of said groups of levers, and devices on said levers pivotally supporting the same on said bridge bearing portions.
- 40 10. In a typewriting machine, the combination with a frame and key levers thereon arranged in groups, of supporting means on the frame for said key levers comprising a one-piece sheet metal bridge having bearing 45 portions struck therefrom extending transversely of the machine in lines spaced relatively to one another from front to rear of the latter, one for each of said groups of levers, devices on said levers pivotally supporting the same on said bridge bearing portions, and a member secured to said bridge and having means for retaining said lever devices on said bearing portions.
- 50 11. In a typewriting machine, the combination with a frame and key levers arranged in groups, of supporting means on the frame for said levers comprising a sheet metal

plate slotted for the reception of the levers with bearing depressions struck therein extending transversely of the machine and spaced relatively to one another from front to rear of the latter to correspond with the different groups of levers, and trunnion means extending from opposite sides of each lever and pivotally supported in the corresponding bearing depression. 65

12. In a typewriting machine, the combination with a frame and key levers thereon arranged in groups, of supporting means on the frame for said levers comprising a sheet metal plate slotted for the reception of the levers with bearing depressions and intermediate projections struck therefrom in lines extending transversely of the machine and spaced from front to rear of the latter, one for each group of levers, trunnion means carried by said levers and resting in said bearing depressions, and a cover plate secured to said projections and provided with means for retaining said trunnion 75 means of the levers in said bearing depressions. 80

13. In a typewriting machine, the combination with a frame and key levers thereon arranged in groups, of supporting means on the frame for said levers comprising a transversely extending sheet metal plate having a series of guide slots therein for the reception of said levers with the metal at the sides of said slots struck in opposite 90 directions to increase the effective depth thereof and to provide bearing portions for said levers, said bearing portions being arranged in lines extending transversely of the machine and spaced from front to rear of the latter to correspond with the different 95 groups of levers, and bearing means pivotally supporting said levers in the respective bearing portions of the plate. 100

14. In a typewriting machine, the combination with a frame and key levers thereon arranged in groups, of supporting means on the frame for said levers comprising a transversely extending, substantially channel-shaped plate of sheet metal formed with a series of guide slots for the reception of said levers and with bearing surfaces for the levers between said slots arranged in lines extending transversely of the machine and spaced from front to rear thereof 105 to correspond with the different groups of levers, and means pivotally supporting the levers on said bearing surfaces. 110

GEORGE F. ROSE
